UNITED STATES PATENT OFFICE

103,131

DESIGN FOR A FLOWER EXHIBITING DEVICE

Robert W. Simpson, New York, N. Y.

Application October 26, 1936, Serial No. 65,496

Term of patent 14 years

To all whom it may concern:

Be it known that I, Robert W. Simpson, a subject of the King of Great Britain, residing in the Borough of Manhattan, city, county, and State of New York, have invented a new, original, and ornamental Design for a Flower Exhibiting Device, of which the following is a specification, reference being had to the accompanying drawing, forming a part thereof, in which

The figure is a perspective view of a flower exhibiting device embodying my design.

I claim:

The ornamental design for a flower exhibiting device as shown.

ROBERT W. SIMPSON.
